UNITED STATES PATENT OFFICE.

MARTIN HARDSCOG, OF OTTUMWA, IOWA

FEED FOR PNEUMATIC TOOLS.

942,066.

Specification of Letters Patent. Patented Dec. 7, 1909.

Application filed April 2, 1907. Serial No. 366,032.

To all whom it may concern:

Be it known that I, MARTIN HARDSCOG, a citizen of the United States, residing at Ottumwa, in the county of Wapello and State 5 of Iowa, have invented certain new and useful Improvements in Feeds for Pneumatic Tools, of which the following is a specification.

It is desirable, in the operation of pneumatic tools, particularly pneumatic drills, to have present a ready means for feeding forward the tool with its operating hammer, and for withdrawing the tool and its operating hammer and other parts connected 15 therewith.

The objects of the present invention are to feed or advance the hammer and the operating tool, with the surrounding casing, by the pressure of the driving medium for the 20 hammer, so that the driving medium for the hammer will serve the double purpose of operating the hammer and of feeding forward or advancing the hammer and tool; to enable a medium under pressure for operating 25 the hammer and tool to be utilized in withdrawing the hammer tool and connected parts; to furnish a fixed tube, for supplying compressed air, or other medium under pressure, to operate the hammer, with a 30 cross head and packing rings encircling its forward end and coacting with a surrounding tube, for the cross head and packing rings to furnish an abutment against which the admitted medium under pressure will 35 act to feed forward or advance the hammer, the operating tool and the tube carrying the hammer and encircling the medium under pressure supply tube; to furnish a fixed outer tube or casing, which casing surrounds 40 the tube carrying the hammer and operating tool, which tube has, adjacent to its outer end, between its wall and the wall of the hammer tube, a head or cross wall to serve as an abutment to coact with a piston or 45 packing ring on the inner or hammer tube, and furnish a chamber into which compressed air, or other medium under pressure, can be forced and act to withdraw the hammer and tool and the parts connected 50 therewith; to enable compressed air, or other medium under pressure, to be utilized in operating the hammer, feeding forward the hammer and tool and the parts connected

therewith, and withdrawing the hammer and the tool and the parts connected therewith in the operation of the drill, or other tool or appliance; and to improve generally the construction and arrangement of the parts by which the utilization of compressed air, or other medium under pressure, is obtained in operating the pneumatic hammer, the tool and the parts connected with the hammer.

The invention consists in the features of construction and combinations of parts hereinafter described and claimed.

In the drawing, Figure 1 is a central longitudinal section of the outer casing or tube and the hammer carrying and feed tube, and the pressure medium supply tube, showing 55 the cross heads or walls and the packing rings forming the abutments and the rotary means for the hammer carrying and feed tube also in section, with the hammer frame and tool in full elevation; Fig. 2 a similar 60 view to Fig. 1, showing the hammer frame with a single spiral instead of a double spiral, and omitting the rotating means for the hammer tube; Fig. 3 a face view of a 65 cup leather packing ring; Fig. 4 a sectional 70 elevation of the ring of Fig. 3; Fig. 5 a sectional plan view of the outer casing, the 75 tube carrying the tool, the tube for the medium under pressure, and the driving gear, on an enlarged scale as compared with Fig. 80 1; Fig. 6 a side elevation, showing the support for the rear end of the mechanism; Fig. 7 a front elevation, partly in section, 85 of the support and parts shown in Fig. 6; and Fig. 8 a detail, partly in section, showing 90 the operating tool and an outer tube or casing for insertion as a backing for the drilled hole.

The feed mechanism is shown in connection with a hammer frame, either with a 95 single spiral or a double spiral on its exterior, in connection with a drill head carrying bits or cutters, but it is to be understood that the feed mechanism is applicable for use with other types of hammer frames, and 100 other tools or instruments than a drill head with bits or cutters. The drill shown has a head with a plurality of bits or cutters, but other forms of bits or cutters could be used.

Upon the outer end of the drill head is an 105 outer or end bit or cutter 1, and interme-

diate bits or cutters 2, and 3, so that the head has a plurality of bits or cutters. The head 4 is of a shape, as to length and width, to receive the bits or cutters, and, as shown, 5 the head has a cross hole 5 to facilitate the removal from the head of the bit or cutter in line with the shank or stem of the head.

The head has a shank 6 to enter the chamber of a barrel 7, for the shank to constitute a driven stem or shank; and the shank 10 is held, so as to have a limited end play in the chamber of the barrel 7, by a key *a* secured in the wall of the barrel and passing through a slot in the shank, shown by dotted lines in Fig. 2, which key prevents the head 15 from falling out in the operation of the drill.

The frame has, circumferentially extending around the barrel 7, two spiral flanges 8, as shown in Fig. 1, or a single spiral flange 20 8, as shown in Fig. 2. Each spiral flange has passages 9, as shown by dotted lines in Figs. 1 and 2, and a port *b*, and a cross passage *c* opening into said passage 9, as shown in Fig. 8. All of these parts are in 25 communication with the chamber of the barrel for inducing and educting a fluid or medium under pressure to operate the hammer within the barrel; and the spiral passages are each connected by a tube 10 with 30 a hole in the drill head, as shown by dotted lines in Figs. 1 and 2.

The spiral flange of Fig. 1, and the spiral flange of Fig. 2, have a projection 11 forming a shoulder 12, which shoulder furnishes 35 a rest for an outer tube or casing *d*, as shown in Fig. 8, which is used as a backing for the drilled hole.

The rear end of the frame and barrel 7 have entered thereinto a closing plug 13 with 40 an induction passage 14, as shown in Fig. 8, constituting means for admitting a medium under pressure to the induction passage of the spiral flanges extending around the barrel 7. The plug 13 has threaded thereunto 45 the forward end of a revoluble and endwise movable tube 15, constituting carrying means for the hammer frame and the feed tube, for supplying a medium under pressure to the tool, and has on its exterior spiral 50 flanges 16 forming a conveyer or flight to coact with the spiral flanges or flange of the frame in removing the cuttings, dust and fine particles from around the bits or cutters at the front of the drill head.

55 A revoluble supply tube 17 for a medium under pressure is entered into the inner tube 15, and is held in a fixed relation against endwise movement with its outer end connected to a hose or other conductor leading 60 from a source of supply for compressed air, or other medium under pressure. The forward end of the supply tube has a cross head or abutment 18, formed or secured thereon and forming a chamber 19 between 65 it and the face of the closing plug 13, into

which chamber compressed air, or other medium under pressure, is discharged to act against the end face of the closing plug and feed forward the hammer frame and tool, and to supply the medium under pressure to 70 the barrel of the hammer frame for operating the hammer in the barrel, which chamber 19 increases in length as the drill gradually advances, carrying with it the inner or feed and hammer carrying tube 15 which 75 is attached to the closing plug 13, so that the hammer, the drill head with its bits or cutters, and the inner or feed and hammer carrying tube 15 all move as one. The forward or discharge end of the supply tube 17, 80 rearward of the cross head or abutment 18, is encircled by a plurality of packing rings 20, each consisting of an outer wall 21, an inner wall 22, with a chamber 23 between the walls, and a hole or opening 24 within 85 the inner wall for the passage of the tube 17; and each packing ring is held in place by the medium under pressure entering the chamber 23 which acts and expands and holds the walls 21 and 22 in close contact 90 with the faces of the medium under pressure-supply tube and the hammer frame feed tube. The packing rings, fitting snugly and tightly against the inner face of the tube 15 and the outer face of the tube 17, furnish a 95 series of abutments, which prevents the compressed air, or other medium under pressure, from escaping between the supply tube 17 and the feed and carrying tube 15, with the result that the compressed air, or other medium under pressure, acts in the chamber 19 against the end face of the cross head or 100 wall 18 and the closing plug 13, to gradually feed forward the frame and the head with the bits or cutters, as the head and the bits or cutters operate to drill or bore the hole. It will thus be seen that the medium under pressure, supplied through the tube 17, furnishes the medium for operating the hammer in the barrel of the frame, and also 105 the medium for feeding forward or advancing the hammer frame, the head with its bits or cutters, and the feed and carrying tube 15, with its conveyer or flight, within which 110 tube the supply tube is located.

The conveyer or flight is encircled by a non-revoluble outer tube or casing 25, which forms a backing for the conveyer or flight in the operation of the drill or other tool, and this outer casing or tube 25 has a fixed 115 relation against endwise movement in the construction shown.

It is necessary, in operating the drill or other tool, for various reasons, to withdraw the hammer carrying or conveyer tube and the hammer frame with the pneumatic hammer and the tool, and the present invention utilizes compressed air, or other medium under pressure, for such withdrawal.

The construction shown has, within and

near the rear end of the outer casing or tube 25, a cross head or abutment 26 fixedly attached in place by lag bolts or screws 27, or otherwise, and at the rear of the cross head 5 or abutment 26, and movable within the outer casing or tube 25, is a cross head, piston or abutment 28, having a neck 29 which threads into the outer end of the carrying tube 15, for the piston and carrying tube to 10 move as one. The head, piston or abutment 28 has circumferential packing rings 30, so as to make a tight joint, between the head, piston or abutment 28 and the inner face of the outer casing or tube 25, against the escape 15 of the medium under pressure when admitted in the space between the fixed cross head or abutment 26, and the movable cross head, piston or abutment 28 for forcing the latter rearward. The movable cross head, 20 piston or abutment is slidable endwise, or longitudinally, on the revoluble supply tube 17, and is connected with such tube by a spline 31 entered into a longitudinal groove 32 in the tube 17, so that the revolving of 25 the tube 17 will revolve the piston, cross head or abutment 28, and with it the feed and carrying tube 15, the hammer frame and the tool in operating the tool. The outer casing or tube 25 has entered thereinto a 30 coupling 33, connected with which is a hose or tube 34, leading to a source of supply for compressed air or other medium under pressure, for admitting compressed air, or other medium under pressure, into the space between the fixed cross head or abutment 25 and the movable cross head, piston or abutment 28, for forcing the movable cross head, piston or abutment rearward to withdraw 35 the carrying tube, the hammer frame and the tool.

The rear end of the outer tube or casing 25 is supported on a frame or standard 35, so as to have a fixed relation to the tube 25. This frame or standard 35, in the arrangement shown, consists of a band *e* encircling the outer casing or tube 25 and having, on opposite sides, projecting pins or studs *f* to enter notches or recesses *g* in a support formed of two side pieces *h*; and the side pieces *h* are connected together at the lower end by a band or cross head *i*, extending down from which is a stem *j* having a sharp point, with grab handles *j'* for the stem. The upper end of the side bars *h* of the support 50 are connected together by a band or cross head *k*, extending up from which is a rod *l*, held in the band or cross head *k* by a locking screw or stem *k'*; and the rod *l* has its upper end entered into a socket *m*, and secured by a locking screw or stem *l'*, the socket *m* having a pointed end, as shown in Fig. 6. The frame or support 35 is held in a fixed position by inserting or forcing the pointed ends of the stem *j* and socket *m* 60 into the material; and the height of the

mechanism is adjusted, as required, by inserting the pins or studs *f* in the proper notches *g* of the side bars *h* of the support.

The outer end of the casing or tube 25 has entered thereinto a block or plug 36, secured in place by lag bolts or screws 37, or otherwise, and this head or block 36 has a central axial chamber, encircling the pressure supply tube 17, which chamber 38 receives thereinto the hub 39 of a bevel gear 40, 70 for the gear to be free to revolve on the head or block as a support. The bevel gear 40 and its hub has a spline 41, which enters the groove 32 of the supply tube 17, so as to interlock the bevel gear with the supply tube 75 for the rotation of the gear to rotate the revoluble supply tube. The bevel gear 40 is driven by a bevel gear or pinion 42 meshing therewith, and the bevel gear or pinion 42 is fixedly secured to a shaft 43, mounted in a 80 box or bearing 44 extending out from the head or block 36, in the arrangement shown. The shaft 43 is connected with a handle 45 by a pin 46, and the handle 45 has a grip 47, by which the handle can be turned to revolve 85 the shaft 43, and through the bevel gear or pinion 42 rotate the bevel gear 40, and transmit rotation to the hammer frame, and the tool carried thereby, through the revoluble supply tube and the feed and carrying tube 90 for the hammer frame.

The rear end of the revoluble supply tube 17 has threaded thereonto two rings forming a head 48 and furnishing a circumferential groove 49, in which is entered a ring 50, 100 which ring has a circumferential passage 51 in its inner face, and this passage 51 is in communication with the interior of the supply tube 17 by ports or passages 52, so that compressed air, or other medium under pressure, can be supplied to the tube 17 without interfering with the rotation of said tube, as the tube is free to rotate within the ring 49 without disturbing the position of the ring. The circumferential chamber or passage 51 105 has, leading out therefrom, on one side, a port or passage 53, into which is entered a coupling 54, to which is connected a hose or other conductor 55, leading from a source of supply for compressed air, or other medium under pressure, so as to supply compressed air, or other medium under pressure, to the tube 17, for the air, or other medium under pressure, to discharge from the tube and feed forward the hammer frame and the tool, and to operate the pneumatic hammer. The construction shown has the rear end of the revoluble supply tube 17 closed by a 110 plate or head 56, fixedly attached to the end of the tube by bolts or screws 57, or otherwise, and, as shown, a fixed rod 58, supported at the rear end against endwise movement by a bumper *n*, entered into the material operated upon or otherwise fixedly held in place with a bearing point 59, abuts against 115

the end head 56, at the center, so as not to interfere with the rotation of the supply tube 17, and at the same time furnish a backing or support against rearward movement of the revolute supply tube from the admission of the medium under pressure into the chamber 19, for feeding forward and operating the tool. The wall of the outer tube or casing 25 forward of its advance end furnishes an opening or hole 60 between the end of the tube or casing 25 and the surface being drilled, for the discharge of the cuttings, dust and fine particles carried back by the spiral flanges and 15 the spiral flange of the conveyer or flight.

The feed of the tool is obtained by compressed air, or other medium under pressure, admitted through the supply tube 17 into the chamber 19 to act against the end face 20 of the closing plug 13, as already explained; and when compressed air, or other medium, is employed for operating the hammer and feeding forward the tool, the air or other medium under pressure is shut off from 25 admission between the tubes 15 and 25 and abutments 26 and 28 so as not to interfere with the forward feed in use. The air, or other medium under pressure, is admitted to the outer tube or casing between the cross 30 wall or abutment 26 and the piston or abutment 28, when it is desired to employ compressed air, or other medium under pressure, to withdraw the conveyer or flight tube and the hammer frame and tool, and when compressed air, or other medium under pressure, 35 is employed for withdrawing purposes, the air, or other medium under pressure, is shut off from the supply tube 17, so as to not have a resistance furnished by the air or other medium under pressure, against the withdrawal of the tube, the hammer frame and 40 the tool. The compressed air, or other medium under pressure, enters the space between the outer and inner tubes in rear of 45 the fixed cross head or abutment 26, so as to press against the front face of the piston or, movable abutment 28, and furnish the requisite force or power to carry back or withdraw the carrying tube 15, the hammer 50 frame and the tool head and tools, which move as one with the cross head or movable abutment. It will thus be seen that compressed air, or other medium under pressure, is utilized, both for operating the tool and 55 for withdrawing the tool when required, and this without any change in the relative arrangement of the parts, except the admission of the compressed air, or other medium under pressure, to the supply or casing tube, 60 or to the outer tube, as may be required, for the compressed air, or other medium under pressure, to serve as the power or force for feeding forward and operating the tool, or for withdrawing the tool and the parts con-

nected therewith. The cross head or wall 65 26 constitutes a fixed abutment, while the cross head or piston 28 constitutes a movable abutment, and when the tool has been advanced to the limit of its operation, the space between the fixed abutment and the 70 movable abutment is correspondingly reduced, so that compressed air, or other medium under pressure, admitted to the space between the fixed abutment and the movable abutment, will act against the fixed abutment 75 and recede the movable abutment or piston, carrying with it the tube fixed thereto, and the hammer frame and tool connected with the tube and withdrawing these parts from the hole made by the tool. 80

What I claim as new and desire to secure by Letters Patent is:

1. In a feed mechanism for a pneumatic tool, the combination of a fixed outer casing, 85 a revolute supply tube located therein for conveying a medium under pressure and held against endwise movement, an abutment secured on the forward end of the supply tube, a revolute endwise movable carrying tube encircling the supply tube and its abutment, 90 means for revolving the carrying tube and a hammer frame connected with the carrying tube and forming a chamber between its rear end and the abutment of the carrying tube, whereby a medium under pressure, 95 when admitted to the chamber, will act on the end of the frame and feed forward the frame and the carrying tube, substantially as described.

2. In a feed mechanism for a pneumatic tool, the combination of a fixed outer casing, 100 a revolute tube located thereon for conveying a medium under pressure and having a fixed relation against endwise movement, an abutment secured on the forward end of the supply tube, a revolute and endwise movable carrying tube encircling the supply tube, 105 means for revolving the carrying tube, a hammer frame entered into the forward end of the carrying tube and forming a chamber between its rear end and the abutment of the supply tube, and a tool carried by the frame, whereby a medium under pressure admitted to the chamber between the 110 end of the frame and the abutment on the supply tube will actuate the tool and feed forward the hammer frame, substantially as described.

3. In a feed mechanism for a pneumatic tool, the combination of a revolute and end 115 wise movable tube carrying a hammer frame, a fixed outer casing encircling the hammer frame carrying tube, a fixed abutment secured within the outer casing, and a piston 120 fixed on the hammer frame carrying tube 125 and adapted to slide within the outer casing, whereby a medium under pressure admitted between the fixed abutment and piston will

act against the piston and withdraw the casting, the carrying tube and the hammer frame, substantially as described.

4. In a feed mechanism for a pneumatic
5 tool, the combination of a revoluble and end-
wise movable carrying tube, a hammer
frame entered onto the forward end of the
carrying tube, a fixed outer casing encircling
the carrying tube, a tool carried by the ham-
10 mer frame, a fixed abutment for the outer
casing between the casing and the carrying
tube, and a piston secured on the outer end
of and endwise movable with the carrying
tube and between the tube and the outer
15 casing, whereby a medium under pressure
admitted between the abutment and movable
piston will act and withdraw the carrying
tube, the hammer frame and the tool, sub-
stantially as described.

20 5. In a feed mechanism for a pneumatic tool, the combination of a revoluble supply tube for a medium under pressure and having a fixed relation against endwise movement, an abutment secured on the forward end of the supply tube, a revoluble and endwise movable carrying tube encircling the supply tube, a hammer frame connected to the forward end of the revoluble and endwise movable carrying tube and forming a chamber between its rear end and the abutment of the supply tube, an outer fixed easing, an abutment secured within the outer casing between the casing and the carrying tube, and a piston attached to the rear end 30 of the carrying tube, the relation of the parts being such that the admission of a medium under pressure to the chamber acts to feed forward the hammer frame and the admission of a medium under pressure between the abutment of the outer casing and the piston acts to withdraw the hammer frame, substantially as described.

35 40

6. In a feed mechanism for a pneumatic tool, the combination of a revoluble supply tube for a medium under pressure and having a fixed relation against endwise movement, an abutment secured on the forward end of the supply tube, a revoluble and endwise movable carrying tube encircling the supply tube, a hammer frame connected to the forward end of the revoluble and endwise movable carrying tube and forming a chamber between its rear end and the abutment of the supply tube, an operating tool carried by the frame, an outer fixed casing, an abutment secured within the outer casing between the casing and the carrying tube, and a piston attached to the rear end of the carrying tube, the relation of the parts being such that the admission of a medium under pressure to the chamber acts to feed forward the hammer frame and the tool, and the admission of a medium under pressure between the abutment of the outer casing and the piston acts to withdraw the hammer

frame and the tool, substantially as described.

7. In a feed mechanism for a pneumatic tool, the combination of a revoluble supply tube for a medium under pressure and having a fixed relation against endwise movement, an abutment secured on the forward end of the tube, a carrying tube encircling the supply tube, a frame connected to the forward end of the carrying tube and forming a chamber between its rear end and the abutment of the supply tube, an operating tool carried by the frame, an outer casing surrounding the carrying tube, an abutment secured to the outer casing between the casing and the carrying tube, a piston attached to the rear end of the carrying tube, means for supplying a medium under pressure to the chamber at the forward end of the carrying tube for the medium under pressure to act and feed forward the hammer frame and the tool, and means for admitting medium under pressure between the abutment on the outer casing and the piston on the carrying tube for the medium under pressure to act and withdraw the hammer frame and the tool, substantially as described.

8. In a feed mechanism for a pneumatic tool, the combination of a tube for supplying a medium under pressure and having a fixed relation against endwise movement, an abutment secured on the forward end of the tube, a revoluble and endwise movable carrying tube encircling the supply tube, a hammer frame connected to the forward end of the carrying tube and forming a chamber between its rear end and the abutment of the supply tube, an outer casing held against rotation and endwise movement and surrounding the carrying tube, a fixed abutment secured on the outer casing, a movable abutment secured on the revoluble and endwise movable carrying tube, both abutments located between the carrying tube and the outer casing, and means for admitting a medium under pressure between the two abutments, substantially as described. 95 100 105 110

9. In a feed mechanism for a pneumatic tool, the combination of a tube for supplying a medium under pressure and having a fixed relation against endwise movement, an abutment secured on the forward end of the tube, a revolute and endwise movable carrying tube encircling the supply tube, a hammer frame connected to the forward end of the encircling tube and forming a chamber between its rear end and the abutment of the supply tube for the medium under pressure, an outer casing held against rotation and endwise movement and surrounding the carrying tube, a fixed abutment secured on the outer casing, a movable abutment secured on the revolute and endwise movable carrying tube, both abutments lo- 130

cated between the carrying tube and the outer casing, means for supplying a medium under pressure to the chamber at the rear of the hammer, and means for supplying a medium under pressure forward of the movable abutment between the outer casing and the carrying tube, substantially as described.

10. In a feed mechanism for a pneumatic tool, the combination of a revoluble and 10 endwise movable carrying tube, a hammer frame connected to the forward end of the carrying tube, an outer casing held against rotation and endwise movement and surrounding the carrying tube, a fixed abutment secured on the outer casing, and a 15 movable abutment on the rear end of the carrying tube, both abutments located between the outer casing and the carrying tube, substantially as described.

11. In a feed mechanism for a pneumatic 20 tool, the combination of a revoluble and endwise movable carrying tube, a hammer frame connected to the forward end of the carrying tube, an outer casing held against rotation and endwise movement and surrounding the carrying tube, a fixed abutment secured on the outer casing, a movable abutment on the rear end of the carrying tube, both abutments located between the outer casing and the carrying tube, substantially as described. 25
